ALWIN G. STEINMAYER, OF CHICAGO, ILLINOIS, ASSIGNOR TO ELECTRICAL ENGINEERS EQUIPMENT COMPANY, OF CHICAGO, ILLINOIS, A CORPORATION OF ILLINOIS.

ELECTRICAL SWITCH.

Application filed January 19, 1924. Serial No. 687,357.

This invention relates to improvements in electrical switches and more particularly to improvements in switches of the disconnecting type, although the invention is not limited to a particular type or class of switches.

In switches for opening and closing electrical circuits, particularly those for opening and closing electrical circuits carrying large quantities of current, the matter of insuring complete and proper contact whenever the switch is closed has presented a difficult practical problem. Improper contact when the switch is closed results in the employment of only part of the material in conducting the current, and this causes overheating or failure of the circuit. Where considerable voltages are carried, the length of the switch arm must be made relatively great for striking distance. Hence, the matter of securing complete and proper closing in spite of disalignment between the separable switch contacts becomes of importance.

The co-pending application of Alfred F. C. Lotz, (case 3), Serial No. 683,572 filed Dec. 31, 1923 is directed to an improved adjustable terminal mounting, in connection with which the present invention is particularly adapted for embodiment, although it is to be understood that the present invention is not limited to combination with that particular contact device. It may be employed with any suitable contact mechanism and in various other types of switches and other apparatus.

In the above referred to application, provision is made for adjusting the separable switch contacts to line them up with respect to each other so that proper closing and uniform contact over the entire contacting surface will be secured. Such a provision is highly desirable, but it is more remedial than preventative. It provides for accurately aligning the contacts, but unless and until such alignment is made slight variations or disalignment may cause very objectionable results.

The primary object of my present invention is the provision of means which will guide the separable contacts into closed position and into uniform and complete contact

whether said contacts are properly aligned or whether they are disaligned with respect to each other. This prevents improper contact and failure of the switch to close before 55 and until the contacts are adjusted into proper alignment where provision for such adjustment is made.

Another object is the provision of an improved auxiliary or arcing contact and the 60 provision of an improved mounting for the arcing contact and main blade mechanism which will be universal in its application to switches, insulator fittings, and other supports of different types and sizes, and 65 which will permit adjustment of the blade mechanism with respect to the contact means with which it cooperates and of the arcing contact with respect to an auxiliary or arcing contact associated with said contact 70 means.

Another object is the provision of an improved movable switch member including an improved blade mechanism and insulating means for supporting said blade mechanism and forming an insulating barrier 75 between the live blade mechanism and the operating mechanism of the switch.

Another object is to minimize the number of parts required and to provide a structure which may be manufactured and assembled at a minimum cost and which may be conveniently taken apart for repairs and replacement and which, when assembled, will be compact and will provide secure and complete electrical connection between the current carrying parts.

According to my invention I employ a pair of floating blades free to be guided into firm, uniform and complete contact with the 90 cooperating contact means, and to prevent improper contact or failure of the switch to close before and until the contacts are adjusted into proper alignment where provision for such adjustment is made, I provide 95 improved guide means for guiding the blade mechanism into closed position. The blade mechanism preferably carries and moves with the guide means as distinguished from relatively stationary guides with respect to 100 which the blade mechanism is movable. Such guides have been arranged at opposite

sides of the relatively stationary switch contacts, and where great disalignment occurs it is possible for them to hinder rather than assist proper closing of the switch.

• I provide a flexible floating guide or funnel shaped member which moves ahead of the switch blade. The guide is flexible in two directions although flexibility in only one direction or in more than two directions 10 is contemplated. The guide need not exactly register the terminal receiving space between the blades with the terminal contact of the switch. Guiding of said space just partially over the nose or end of the 15 terminal contact is usually sufficient, the floating action of the blades permitting complete and proper closing of the switch when closing is started by the guide.

To the end of simplifying and improving 20 the construction and minimizing the number of parts, the guide means is preferably carried by the means provided for tensioning or drawing the blades together and its mounting is preferably such that it spaces 25 the blades to properly receive the cooperating contact therebetween. The guide is mounted along the edges of the blade mechanism and in substantially the plane of the thickness or the transverse dimension of the 30 contact when the switch is closed and it has a flared mouth projecting laterally from the blade mechanism and defining an opening in alignment with the contact receiving space between the blade members. The 35 guide means is movable over the contact ahead of the blade members.

The auxiliary or arcing contact mounting is universal in its application to switches and supports of different types and sizes, 40 and it permits adjustment of the arcing horn or contacts by motion of translation in different planes. The mounting of the blade mechanism is likewise universal in its application to switches and supports of different types and sizes, and it permits adjustment of the blade mechanism with respect to the cooperating contact means by motion of translation in different planes. The mounting of the arcing horn, blade 45 mechanism and contact means for connecting the same to the desired circuit is exceedingly compact, and provides firm and complete electrical connection between the current carrying parts. A protecting hood shields the blade mechanism and the guide means therefor and also the cooperating contact means when the switch is closed, and an improved terminal contact is provided 50 for cooperation with the blade mechanism.

60 To acquaint those skilled in the art with the manner of constructing and practicing the present invention, I shall now describe in connection with the accompanying drawings, a specific embodiment of the same.

65 In the drawings,

Fig. 1 is a side elevational view of a switch embodying the invention;

Fig. 2 is an enlarged fragmentary side elevation of the movable blade and cooperating contact mechanism therefor;

Fig. 3 is a detailed section on line 3—3 of Fig. 2;

Fig. 4 is a detailed section on line 4—4 of Fig. 2;

Fig. 5 is a detailed section on line 5—5 of Fig. 2; and

Fig. 6 is a detailed section on line 6—6 of Fig. 2.

Referring to the drawings, 5 designates the relatively stationary terminal contact of the switch and 6 the movable contact or blade means cooperable with contact 5 to close the switch and separable from contact 5 to open the switch.

Terminal contact 5 comprises a strip, preferably of rolled copper, having one-half reflexed or doubled back on the other half and its free ends turned out at substantially right angles to provide mounting lugs 7 and 8. Terminal 5 is preferably adjustably mounted upon the outer end of a supporting insulator 10 by means of an adjustable mounting 11, such as that more fully disclosed in the co-pending application of Alfred F. C. Lotz, case 3, Ser. No. 683,572, filed Dec. 31, 1923, although it may be mounted in any other suitable or preferred manner. Terminal 5 is secured upon mounting 11 by bolts 12. The clip 5 is simple and inexpensive and its doubled or reflexed formation imparts a desirable yieldability and outward spreading tendency of the opposite sides into firm electrical contact with the cooperable blade or contact members.

The terminal clip 5 is preferably of wrought metal which is highly desirable for securing the desired strength, the structure of the clip shown lending itself peculiarly to formation of the clip of wrought metal. The doubled formation provides a laminated clip, the outer ends of which are integral or connected. This provides a desirable laminated clip in which excellent conducting of the current is secured and separating or fraying of the outer ends of the clip is prevented.

Adjustable mounting 11 is mounted upon an adapter 13 which is in turn mounted upon an insulator fitting 14 on the outer end of insulator 10. Insulator 10 is supported obliquely at its opposite end by a base fitting 15 mounted upon one end of the switch supporting base or slab 16.

At the opposite end of base 16 is mounted an insulator fitting 18 carrying an insulator 19 substantially normal to base 16. The movable contact or blade means 6 is carried upon the outer end of a rocking or tilting insulator 20 mounted upon a rock shaft 21.

Shaft 21 is journaled in a bearing 22 mounted upon base 16 between insulators 10 and 19.

For the purpose of rocking shaft 21 and thereby insulator 20 to open and close the switch, an operating crank 23 is fixed on shaft 21 and provided with an apertured segment 24 for adjustable connection with a connecting member 25 at the upper end 10 of an operating rod 26. The lower end of rod 26 is connected through a clevis 27 with an operating handle 28, so that by grasping handle 28 and pulling it in a counterclockwise direction, shaft 21 and insulator 20 will be rocked in a counterclockwise direction to separate blade member 6 from contact 5 and by swinging handle 28 in the opposite direction shaft 21 and insulator 20 will be rocked in the opposite direction to close the contacts. A stop bracket 30 mounted on base 16 limits the tilting or rocking movement of insulator 20 in a counterclockwise direction. The switch is shown arranged in horizontal position in Fig. 1 with operating shaft or 25 rod 25 extending vertically, but it is to be understood that the switch and operating rod may be mounted and arranged in any other desired manner.

On the outer end of insulator 20 is an 30 insulator fitting 31, and mounted upon said fitting 31 is an adapter fitting 32 having an outer mounting flange 33. A pair of blade members 34 having mounting bases 35 turned out at right angles are mounted upon 35 the outer flange 33 of adapter 32 and project out normal to said flange and from the upper end of insulator 20 in the direction of its length.

Blade members 34 are of suitable conducting material and their outwardly projecting portions are spaced to receive the contact terminal or tongue 5 between them and make electrical contact with the opposite sides of said tongue when the switch is closed. The 45 blade members 34 are forced toward each other by spring washers 36 which spring washers maintain a uniform spring pressure upon blades 34 over substantially their entire areas of contact with terminal tongue 5 to hold the blades firmly and uniformly against the opposite sides of terminal tongue 5 when the switch is closed. Excellent contact and employment of all of the conducting material in carrying current is thus assured. For clamping spring washers 36 against the opposite sides of blade members 34, I provide a pair of plates 37, between one of which and the adjacent blade member one spring washer is confined and the other spring washer is confined between the other blade member, and the other clamping plate. Each plate 37 has an aligning stud 38 which engages in an axial opening in the spring washer and holds the same properly in place. 60 The clamping plates 37 and thereby the

spring washers 36 are clamped in place by bolts 39, the shanks of which extend through aligned openings in plates 37 and blade members 34, clear of the opposite edges of terminal tongue 5. Plates 37 and bolts 39 together form a frame between which the spring washers 36 force blade members 34 towards each other. Blade members 34 are thus securely and uniformly held against the opposite sides of terminal 5 and the 75 spring pressure maintained over substantially the entire contacting area is adjustable by means of bolts 39.

The spring washers 36 hold the blade members yieldingly together and the blade members are floating and free to adapt themselves readily to the sides of the terminal tongue 5. Disalignment between the blade members and terminal 5 may result in engagement of one of the blade members with the outer end of tongue 5 in closing, or closing might be otherwise prevented or contact when closed may be otherwise impaired by such disalignment. The blades would be free to adjust themselves to the sides of the terminal 5, but disalignment might prevent such adjustment. Slight play in the rocking insulator or inaccurate construction or assembly might cause this, for example. To prevent this and to insure proper guiding of blade members 34 over terminal tongue 5, I provide a guide member 40.

This guide member 40 has a pair of arms 41 which project between blade members 34 clear of the opposite edges of clip 5 and in substantially the plane of said clip. Arms 41 are apertured to permit the shanks of bolts 39 to extend through them. The guide member is in this manner mounted between the blade members on the tension bolts therefore and the ends of arms 41 by their disposition between the blade members 34 form spacers for limiting the movement of the blade members toward each other when the switch is open. Their thickness is preferably less than the thickness of terminal tongue 5 so as to not interfere with the proper engagement of the blade members with the sides of the terminal. At the forward ends 100 of arms 41 is a mouth piece 42 which, in the closing movement of the switch, moves over terminal tongue 5 ahead of blade member 34 and guides the blade members properly over the terminal lug. The end of the mouth opening 43 adjacent blade member 34 is of a width substantially equal to the thickness of tongue 5 so that the tongue will be guided into place without appreciable play to interfere with proper closing. From the 105 blade end the side walls of the mouth opening flare outwardly (Figs. 3 and 5) to provide a relatively large opening at the opposite contact receiving end, so that even with considerable disalignment between tongue 5 and the contact receiving space between 110 120 125 130

blade members 34 the larger end of the mouth piece will engage over the tongue and the flared sides of the mouth piece will, in the closing movement of the switch, center the tongue receiving space between blades 34 with tongue 5 and guide the blades properly over the tongue.

In closing the switch the guide moves ahead of the blades. The openings in guide arms 41 are preferably sufficiently large to provide a clearance, as shown in Fig. 4, between said arms and the shanks of bolts 39. This permits flexibility or floating of the guide in a vertical direction as viewed in Fig. 4 and the floating action along the shanks of bolts 39 permits flexibility or floating of the guide in a direction substantially normal to said first plane. This permits and assures proper guiding action of the guide over clip 5 ahead of the blade mechanism in the closing of the switch.

Mounted over blade member 34 and upon the flange 33 of adapter fitting 32 is an arcing horn clamp 45 comprising an upper clamping member 46 and a lower clamping member 47 having aligned openings 53 through which blade members 34 extend. Clamped between the clamping member 47 and the mounting flanges 35 of blade members 34 and in firm electrical contact with said mounting flanges is a contact plate 48. Contact plate 48 has slots 49 extending in from one end and blade members 34 extend up through said slots. The opposite end of plate 48 is turned or flared down and between said plate 48 and a pair of similarly flared plates 50 and in electrical connection with plate 48 the ends of a pair of flat flexible conductors 51 are clamped by bolts 52.

The terminal tongue 5 and blade members 34 are protected from the action of arcing upon opening the switch by a pair of arcing horns 54 and 55 arranged to separate after separation of blade members 34 from contact 5, so as to draw any arc, as well understood in the art. Arcing horn 54 is carried by and electrically connected with blade members 34, while horn 55 is carried by and electrically connected with terminal 5. One end of horn 55 is secured by clamping straps and bolts 56 to pedestal 57 of the adjustable terminal mounting 11. The opposite end of horn 55 is of triangular formation and lies along one side of horn 54 to cooperate laterally therewith during and after separation of blades 34 from contact 5.

Horn 54 projects out lineally from the end of insulator 20 and its inner end is turned substantially normal to the projecting arcing end and out at 58, over at 59 and back at 60 (Fig. 6) forming a generally rectangular mounting portion. Horn clamping members 46 and 47 have lateral wings 61 and 62 respectively, provided with sup-

plemental angle grooves 63 in which and between members 46 and 47 the out and back turned portions 58 and 60 of horn 55 are clamped. Common bolts 65, the shanks of which extend through aligned openings in members 46 and 47 and through aligned opening in contact plate 48, mounting flanges 35 of blade members 34 and through openings in adapter flange 33, clamp members 46 and 47 together with horn 55 secured therebetween and the horn clamp, contact plate 48 and blade members securely in place on flange 33 with contact plate 48 in firm electrical engagement with blade members 34 and in firm electrical engagement with the horn mounting members and thereby in electrical connection with horn 54. Clamp members 46 and 74, in addition to mounting arcing horn 55 connect said horn electrically with contact plate 48 and thereby electrically in circuit with blade members 34.

As shown, the openings in clamp members 46, 47 and in flange 33, contact plate 48 and base flanges 35 are all elongated. This permits variation in positioning of bolts 65 and makes the mounting of the blade members and horn clamps universal in their application to adapters, fittings and other supports of different styles and sizes. Elongation of said openings also permits a certain degree of adjustment of the blade members and other parts by motion of translation, which is highly desirable. Bolts 65 clamp the parts securely in adjusted position.

Flat flexible conductors 52 extend and are electrically and mechanically connected at their opposite ends between a pair of flared terminal plates 70 mounted upon a clip support and strain clamp 71 on the outer end of insulator 19. Clamp 71 is bolted to an adapter fitting 72 which is in turn mounted upon an insulator fitting 73 on the outer end of insulator 19. Line conductor 74 is connected into a terminal socket 75 bolted upon the projecting end of lower terminal plate 70 and said conductor 74 is clamped to and supported by clamp 71 at 76. The other line conductor 78 is clamped to and supported at a distance from its end at 79 to one of the adjustable mounting members 11 and at its end said conductor 78 is connected into a terminal socket 80 bolted upon a terminal plate 81 clamped beneath the heads of bolts 12 which secure terminal tongue 5 in place.

Lower clamping member 47 has an upturned boss 82 to the opposite ends of which a pair of toggle links or arms 83 are pivoted by a bolt 82'. The opposite ends of links 83 are pivoted at 84 to toggle links 85 which are in turn pivoted at their opposite ends at 86 to clamp 71. Flexible conductors 51 are supported at spaced points 87 along links 83 and 85. In rocking insula-

tor 20 to open and close the switch, toggle links 83 and 85 buckle and open to control the rocking movement of insulator 20 and the slack produced in the flexible portions 5 of conductors 52 is taken care of by this action of the toggle and no undue stress or bend is occasioned at any point in the conductors.

To protect the blade members 34 and contact 5 against snow, sleet, frost accumulations and the like, I provide a protecting hood 90 having substantially parallel sides 91, an open front 92, a closed rounded back 93 merging into a closed rounded top 94. 10 Adjacent open front 92, sides 91 have depending lugs 95 pivoted upon a pin 96 journaled at its opposite ends in lugs 97 on clamp member 46. A torsion spring 98 coiled about the opposite ends of pins 96 has its opposite ends extending out along the open bottom of the hood and turned out at 99 to cooperate with the lower edges of sides 91. The intermediate portion of spring 98 is offset at 100 and said offset 100 engages the 15 top of clamp 46 to prevent turning of the spring on pin 96 and to limit uncoiling of the intermediate portion of the spring. A lug 102 on the interior of back 93 cooperates with the edges of blade members 34 to limit 20 the swinging of the hood in the direction of its closing movement when the switch is opened.

As the switch is opened, hood 90 is swung by spring 98 into more complete closing position over contact means, 6, the movement of hood 90 in said direction being limited by engagement of lug 102 with blade members 34. In closing, the switch hood 90 yields to permit proper engagement of the blades with 25 tongue 5 after the hood has reached the limit of its movement with insulator 20. The hood completely covers and protects blade members 34, guide means 40 and contact 5 when the switch is closed, and when 30 the switch is opened it covers and protects the blades or movable switch members. Swinging of the hood about pin 96 in a clockwise direction, as the switch opens, increases the covering of the movable switch 35 means as the rocking insulator approaches vertical position.

From the foregoing it will now be apparent that I have provided for guiding the blade members into cooperation and uniform contact with terminal lug 5 in spite of disalignment therebetween. The guide means provided, in conjunction with the floating action of the blade members assures complete and uniform contact when the switch 40 is closed and assures proper closing in spite of disalignment and until the separable contacts are adjusted into alignment where such an adjustment is provided. Incomplete or entire failure to close, due to failure to adjust the contacts before the closing opera-

tion, is thus prevented. If considerable disalignment is noted by the action of the guide in closing, it may be removed by adjusting the contact into proper alignment, but adjustment means for doing this is not essential to the practicing of the present invention. Relatively great disalignment may increase the action of the guide, but it will be taken care of by said guide.

The guide is carried by and moves with 75 the movable blade members. Its mounting is in substantially the plane of the contact receiving opening between said members and common means tensions the blade members and secures the guide in place. The flared mouth of the guide projects laterally from the blade members and moves over the relatively stationary contact 5 ahead of said blade members. These items are all individually important in that each contributes 80 to the desired end. While the particular means disclosed for securing them is considered important, other manners of attaining these ends and carrying out said items 85 are contemplated.

The mounting of arc horn 54 between members 46 and 47 permits adjustment of the arcing horn by a motion of translation to the right or left in Fig. 6. The elongated openings through which bolts 65 extend permit adjustment of the arcing horn by a motion of translation in a different plane or up-and-down, as viewed in Fig. 6. The elongated openings through the base of blade members 34 permit adjustment of said blade members by a motion of translation to the right or left, as viewed in Fig. 4, and the elongated openings through contact plate 48 permit adjustment of said plate by a motion of translation in the same direction. The 90 elongated openings in flange 33 assist said 95 adjustments and allow for variation in the positioning of bolts 65 and also permit universal adaptation of the blade and arc horn mounting members and contact plate to fittings and supports of different types and sizes, as well as permitting variation in construction and assembly. This arrangement also adapts fitting 32 for receiving mountings of different types and sizes.

The clamping of horn 54, mounting members 46 and 47, blade member 34 and contact plate 48 all together and in proper electrical connection on flange 33 provides an exceedingly compact arrangement, minimizes the 105 number of parts and simplifies and decreases the cost of construction and assembly. The advantages of the construction of terminal clip 5 and of the arrangement of hood 90 have already been pointed out. The mounting of the separable contacts of the switch on the adjacent ends of insulators inclined toward each other, shortens the striking distance and the mounting of the blade members on the outer end of insulator 20 shortens 110 115 120 125 130

the length of said blade members. This minimizes the play and disalignment which will occur in said members with respect to contact 5. It permits the use of floating blades, yet confines the floating action to the contact making area where it is desired, and the objectionable results of a floating action of the blades down to the point of mounting or to the point of pivotal action thereof is avoided. At the same time insulator 20 forms an insulating barrier between the blade members and the switch operating mechanism and confines the live parts of the switch to an exceedingly compact space.

I claim:—

1. In combination, floating blades, tension bolts passing through said blades and guide means carried by said bolts.
2. In a switch, the combination of a pair of floating blades of guide means mounted between and spacing said blades.
3. In a switch, the combination of a pair of floating switch blades, a guide carried by and projecting laterally from said blades, said guide having a portion lying between the blades and means for mounting said portion between the blades and tensioning said blades.
4. In a switch, the combination of a pair of floating switch blades, a contact cooperable therewith and a guide carried by the blades and mounted equally on opposite sides of the contact receiving portion thereof.
5. In a switch, the combination of a contact, a switch member movable into and out of cooperation with said contact, and a guide for guiding said switch member into cooperation with said contact, the mounting of said guide being positioned along the edge of the contact when the switch is closed.
6. In a switch, the combination of a contact, a switch member movable into and out of cooperation with said contact, and a guide for guiding said switch member into cooperation with said contact, the mounting of said guide being positioned in substantially the plane of the transverse dimension or thickness of the contact.
7. In combination, a contact member, a switch blade cooperable therewith, said switch blade comprising spaced blade members having their ends turned out at substantially right angles and provided with elongated apertures, spring means lying outside the blades for pressing them upon the contact member and means not thicker than the contact for spacing the blades apart when in open position.
8. In a switch, the combination of a relatively stationary terminal contact, floating blades movable into and out of cooperation with said contact and adapted to embrace opposite sides of said contact when the switch is closed, bolt means operating in ten-

sion to limit separation of the blades, and a guide for guiding the blades over said terminal contact, said guide having a portion lying between the blades and mounted upon said bolt means.

9. In a switch, the combination of a relatively stationary terminal contact, floating blades movable into and out of cooperation with said contact and adapted to embrace opposite sides of said contact when the switch is closed, bolt means operating in tension to limit separation of the blades, a guide for guiding the blades over said terminal contact, said guide having a portion lying between the blades and mounted upon said bolt means, and a flared mouth extending laterally from the blades.

10. In combination, a contact member, a pair of blade members cooperable therewith, means for guiding said blade members into cooperation with the contact member, said guide means spacing said blade members.

11. In combination, a fitting having a mounting flange, said flange having elongated openings, a pair of blade members having turned out mounting bases, said bases having elongated openings, a pair of clamping members supporting an auxiliary arcing contact and having elongated mounting openings, and bolt means passing through the elongated openings in said blade members, clamping members and fitting flange for clamping said members together, and in firm electrical contact.

12. In combination, a fitting having a mounting flange, said flange having elongated openings, a pair of blade members having turned out mounting bases, said bases having elongated openings, a pair of clamping members supporting an auxiliary arcing contact and having elongated mounting openings, and bolt means passing through the elongated openings in said blade members, clamping members and fitting flange for clamping said members together, and in firm electrical contact, a contact plate clamped in place with said bolt means and a conductor connected to said plate.

13. In a switch, a relatively stationary terminal contact, a rocking insulator, a pair of floating blades carried by said insulator, means for rocking said insulator to move the floating blades into and out of cooperation with said relatively stationary terminal contact, means for applying pressure to the outside of the blades and means not thicker than the contact for spacing the blades apart when in open position.

14. In a switch, a relatively stationary terminal contact, a rocking insulator, a fitting on one end of said insulator, auxiliary arcing contact supporting means mounted upon said fitting, a pair of spaced blade members having out-turned mounting bases mounted upon said fitting beneath said

auxiliary arcing contact supporting means, means for applying pressure to the outside of the blades and means not thicker than the contact for spacing the blades apart when in open position.

15. In a switch, a relatively stationary terminal contact, a rocking insulator, a fitting on the outer end of said insulator, auxiliary arcing contact supporting means mounted upon said fitting, a pair of spaced blade members having out-turned mounting bases and a contact plate mounted with the mounting bases of the blade members upon said fitting with said auxiliary arcing contact supporting means, and means carried by and adapted for guiding the blade members into closed position.

16. In combination, a relatively stationary switch terminal, a rocking insulator, a pair of floating blades mounted upon said insulator and adapted for movement into and out of engagement with the relatively stationary switch terminal by rocking of the insulator, means for applying pressure to the outside of the blades and means not thicker than the terminal for spacing the blades apart when in open position.

17. In a switch, a movable switch member comprising an insulator, spaced floating switch blades on said insulator, a terminal contact cooperable with said blades, means for applying pressure to the outside of the blades and means not thicker than the contact for spacing the blades apart when in open position, said spacing means being separate from the blades and the blades being movable free of said spacing means.

18. In combination, a rock shaft, an insulator mounted on said shaft to rock therewith, a pair of relatively short floating blades on the opposite end of said insulator, a relatively stationary terminal contact cooperable with said blades, means for applying pressure to the outside of the blades and means not thicker than the contact for spacing the blades apart when in open position.

19. In a switch, a pair of insulators inclined toward each other and one movable relative the other, contact means on one of said insulators, a pair of floating blades mounted on the adjacent end of the other insulator and movable into and out of cooperation with said contact means, means for applying pressure to the outside of the blades and means not thicker than the contact for spacing the blades apart when in open position.

20. In a switch, a common supporting base, an inclined insulator mounted on said base, contact means on said insulator, a rock shaft journaled on said base, an insulator mounted on said shaft to rock therewith and inclined toward said first insulator when in closed position, a pair of floating switch blades mounted on said rocking insulator ad-

acent the contact means on said first insulator and adapted for movement into and out of cooperation with said contact means by the rocking of said second insulator, means for applying pressure to the outside of the blades and means not thicker than the contact for spacing the blades apart when in open position.

21. In a switch, the combination with separable contact means, of means for guiding said contact means into cooperation, said guide means being floating in a plurality of directions.

22. In a switch, a common supporting base, an inclined stationary insulator mounted on said base, stationary contact means on said insulator, a rock shaft journaled on said base in substantially the plane in which said inclined stationary insulator is mounted on said base, an insulator mounted on said rock shaft to rock therewith, contact means on the rocking insulator said rocking insulator having its outer end inclined toward the outer end of said stationary insulator when the contact means thereon is in engagement with the contact means on the stationary insulator, the inclination of said first insulator permitting faster engagement and disengagement between said contact means on movement of the rocking insulator and the contact means on the stationary and rocking insulators being formed to permit adequate opening or separation thereof solely by the rocking movement of one insulator and notwithstanding the inclination of the upper end of the other insulator toward same.

23. In a switch, a common supporting base, a rocking insulator mounted thereon, an inclined stationary insulator mounted thereon in substantially the plane in which said rocking insulator is mounted on said base, contact means on each of said insulators adapted for engagement with each other, said insulators being inclined toward each other when the contacts thereon are in engagement to insure positive engagement of said contact means and the contact means on the stationary and rocking insulators being formed to permit adequate opening or separation thereof solely by the rocking movement of one insulator and notwithstanding the inclination of the other insulator toward the same.

24. In a switch, a fixed member having a base plate fixed thereto, flexible conductor means secured to said base plate by a clamping plate, said clamping plate having a curved guide integral therewith for controlling the flexing of said conductor means.

25. In a switch, a fixed member having a base plate fixed thereto, said base plate having an extension integral therewith, a socket having a conductor secured therein bolted to said base plate, said conductor being also

secured to the integral extension of said base plate by suitable bolt means.

26. In combination, a fitting having a mounting flange, said flange having a plurality of openings, a pair of blade members having turned-out mounting bases, said bases having a plurality of openings, a contact plate having a plurality of openings, and bolt means passing through the openings in said flange, blade members and contact plate, for clamping said members firmly together.

27. In a switch, a fitting, a pair of switch blades, a contact plate, a pair of flexible conductor members secured to said contact plate, and bolts passing through the switch blades and through the contact plate for securing said switch blades and contact plate to said fitting.

28. In a switch, an insulator, a pedestal mounted thereon, a terminal mounting adjustably secured to said pedestal, a contact terminal on said adjustable terminal mounting and adjustable relative said pedestal, and flexible conductor means electrically connecting said contact terminal with said pedestal.

29. In combination, floating blades, tension means for said blades, said tension means including tension bolts, passing through said blades and guide means independent of said tension means and carried by said bolts.

30. In a switch, the combination of a pair of floating blades, tension means for said

blades, a contact cooperable with said blades, and a guide independent of said tension means, said guide being carried by the blades and mounted equally on opposite sides of the contact receiving portions thereof.

31. In a switch, the combination of a contact, a switch member movable into and out of cooperation with said contact, tension means for the switch member and a guide independent of said tension means for guiding said switch member into cooperation with said contact, the mounting of said guide being positioned along the edge of the contact when the switch is closed.

32. In a switch, a frame, a stationary insulator supported on said frame, a stationary switch contact mounted on said insulator, a bearing supported on said frame, an insulator mounted for rocking motion on said bearing, said insulator having a cooperating contact adapted to be brought into and out of engagement with the first contact by rocking of said insulator in said bearing, a sleet hood covering both of said contacts when they are in engagement, and arcing horns mounted on top of the insulators below said contacts and disposed laterally of the contacts to clear said sleet hood laterally and in operative alignment with each other.

In witness whereof, I hereunto subscribe my name this 31st day of December, 1923.

ALWIN G. STEINMAYER.
